(57) **CLAIM**

The ornamental design for a switching device, as shown and described.

DESCRIPTION

FIG. 1 is a front perspective view of a switching device;

FIG. 2 is a front view of a switching device;

FIG. 3 is a back view of a switching device;

FIG. 4 is a left view of a switching device;

FIG. 5 is a right view of a switching device;

FIG. 6 is a top view of a switching device;

FIG. 7 is a bottom view of a switching device; and,

FIG. 8 is another front view of a switching device.

The broken lines in the drawings illustrate portions of the switching device that form no part of the claimed design.

1 Claim, 8 Drawing Sheets
